FELIX TOBIEN, OF ESSEN, GERMANY, ASSIGNOR TO FRIED. KRUPP AKTIEN-
GESELLSCHAFT, OF ESSEN-ON-THE-RUHR, GERMANY.

OVERLOAD SWITCH FOR MOTORS.

Application filed December 29, 1921. Serial No. 525,695.

To all whom it may concern:

Be it known that I, FELIX TOBIEN, residing at Essen, Germany, a citizen of the German Republic, have invented a certain new and useful Improvement in Overload Switches for Motors, of which the following is a specification.

This invention relates to overload switches for motors, which are started by means of a starting resistance.

The object of the invention is to provide an overload switch, the sensitiveness of which automatically varies during the starting and which, when used for the protection of motors which are connectible in series-parallel relation, undergoes a variation when the connection is changed from series to parallel.

An embodiment of the invention is diagrammatically illustrated in the drawing, when the overload switch serves to protect two car motors connectible in series or in parallel.

Fig. 1 showing the switch in operative position when the motors are in series, and

Fig. 2 showing the same when the motors are connected up in parallel.

To the current collector B, running on the overhead conductor A, are connected in series, in the arrangement of Fig. 1, the main circuit breaker coil C and the circuit breaker, composed of two fixed contacts C¹ and C² and a movable contact C³, of the overload switch, the starting resistance D with slide contact d¹, and the two car motors E E¹ and F F¹, provided with series field windings. The field winding F¹, of the second motor F F¹, has one terminal connected to earth. With the coil C and the contacts C¹ C², connected with it in series, of the overload switch is connected in parallel a branch circuit which contains a magnet coil C³, acting in the same direction as the coil C, and a series resistance C⁴. The exciting force of said coil C³, which works on the same magnetic circuit as the coil C, is so proportioned that it cannot open the closed overload switch but tends to hold the opened switch against the force of a spring C⁷, connected to the movable contact C³. Another magnet coil C⁵ is connected through a resistance G on one side to earth and on the other side to the point of connection of the two motors. This coil C⁵ also works in the same direction as the main circuit breaking coil C.

The coil C⁵ and resistance G are so proportioned that the coil C⁵, when the motors are running at full speed and the starting resistance D is consequently short-circuited, can furnish as great an exciting force as the main coil C.

In Fig. 2 the motors E E¹ and F F¹ are not connected in series but in parallel. The points of the circuit, to which the magnet coil C⁵ and the resistance G are connected, are connected together by a shunt wire H, so that they represent at this time points of equal potential. The slide contact d¹ is in such a position, as in Fig. 1, that the starting resistance D is fully cut in.

When all the parts are in the position shown in Fig. 1, in which particularly the two motors are connected in series, the overload switch is closed and the slide contact d¹ is so placed that the starting resistance D is fully cut in, then the magnet coil C⁵ receives no current, since the entire line potential is consumed (up to a practically negligible amount) in the starting resistance D. Consequently the only active coil is the circuit breaker coil C; so that the overload switch has only a slight sensitiveness. In proportion as the starting resistance D is being diminished, the portion of the line potential impressed upon the motor F F¹ and therewith the number of revolutions of the motors increases, the current in the magnet coil C⁵ rises, so that the magnetic circuit of the overload switch becomes more and more strongly excited. But at the same time the sensitiveness of the overload switch increases, until it attains its highest value when the starting resistance is short-circuited.

In changing to the parallel connection of the motors E E¹ and F F¹ (Fig. 2), the following connections are established by the controller switch (not shown); first the connection between the field winding E¹ and the armature F is broken; secondly the armature E is connected with the armature F through a conductor J and the field winding E¹ with the field winding F¹ through the conductor H, and thirdly the slide contact d¹ comes again into that position in which the starting resistance D is fully cut in. The ends of the branch circuit, containing the magnet coil C⁵ and the resistance G, remain conductively connected with the field windings E¹ and F¹. Said branch circuit is therefore now short-circuited by the wire H. Con-

sequently in all positions, which the slide contact d^1 can take, the magnet coil C^1 remains unexcited, so that the sensitiveness of the overload switch assumes the same value as at the beginning of the starting when the motors $E E^1$ and $F F^1$ are connected in series.

Without in any way changing the invention, the two motors connectible in series and parallel could be replaced by a single motor and the strength of the exciting current be made dependent upon the fall of potential in said motor. In this case, the resistance G can be so proportioned that the overload switch is twice as sensitive when the starting resistance is short-circuited, as when the latter is fully cut in.

Claims:

1. An electrical system of connections comprising an electrical translating device; a starting current-diminishing means for the protection of said translating device and an electromagnetic overload switch comprising a main current control coil tending to open said switch, a second coil operatively connected across said switch and adapted to retain said switch in open condition, and a third coil operatively connected to said translating device to increase the sensitiveness of said overload switch when the current-diminishing means is gradually eliminated.

2. An electrical system of connections comprising an electrical translating device; a starting current-diminishing means for the protection of said translating device and an electromagnetic overload switch comprising a main current control coil tending to open said switch, a second coil operatively connected to said switch in series with a resistance and adapted to retain said switch in open condition, and a third coil operatively connected to said translating device to increase the sensitiveness of said overload switch when the current-diminishing means is gradually eliminated.

3. An electrical system of connections comprising a number of electrical motors; a starting current-diminishing means for the protection of said motors and an electromagnetic overload switch comprising a main current control coil tending to open said switch, a second coil operatively connected to said switch and adapted to retain said switch in open condition, and a third coil operatively connected to one of said motors to increase the sensitiveness of said overload

switch when the current-diminishing means is gradually eliminated.

4. An electrical system of connections 60 comprising an electrical translating device; a starting current-controlling means for the protection of said translating device and an electromagnetic overload switch comprising a main current control coil tending to open 65 said switch, a second coil operatively connected to said switch and adapted to retain said switch in open condition, and a third coil normally shunted across said translating device to increase the sensitiveness of said 70 overload switch when the current-controlling means is gradually eliminated.

5. An electrical system of connections comprising an electrical translating device; a starting current-controlling means for the 75 protection of said translating device and an electromagnetic overload switch comprising a main current control coil tending to open 80 said switch, a second coil operatively connected to said switch in series with a resistance and adapted to retain said switch in open condition, and a third coil connected in series with another resistance and normally shunted across said translating device 85 to increase the sensitiveness of said overload switch when the current-controlling means is gradually eliminated.

6. An electrical system of connections comprising two electric motors; a starting current-controlling means for the protection 90 of said motors and an electro-magnetic overload switch comprising a main current control coil tending to open said switch and an auxiliary control coil normally connected in shunt with one of said motors when the motors are in series but short circuited when the motors are in parallel. 95

7. An electrical system of connections comprising two electric motors; a starting current-controlling means for the protection 100 of said motors and an electro-magnetic overload switch comprising a main current control coil tending to open said switch, a second coil operatively connected to said switch and adapted to retain said switch in open 105 position, and an auxiliary control coil normally connected in shunt with one of said motors when the motors are in series but short-circuited when the motors are in parallel. 110

The foregoing specification signed at Essen, Germany, this 28th day of November, 1921.

FELIX TOBIEN.
